UNITED STATES PATENT OFFICE.

ALBERT H. LEVENE, OF ROCHELLE PARK, NEW JERSEY.

METALLIC PARTITION.

1,054,575.

Specification of Letters Patent.

Patented Feb. 25, 1913.

Application filed May 4, 1912. Serial No. 695,182.

To all whom it may concern:

Be it known that I, ALBERT H. LEVENE, a subject of the Czar of Russia, and a resident of Rochelle Park, in the county of 5 Bergen and State of New Jersey, have invented a new and Improved Metallic Partition, of which the following is a full, clear, and exact description.

The object of the invention is to provide 10 a new and improved metallic partition for use in offices, stores and other places, and arranged to permit of readily assembling the parts in a correspondingly short time, and to render the partition exceedingly 15 strong and durable.

For the purpose mentioned use is made of hollow main posts adapted to rest on the floor, extension posts adjustably mounted in the said hollow posts projecting upwardly 20 beyond the same, ceiling bars connecting the upper ends of the extension posts with each other, attaching means adapted to connect the ceiling bars with the ceiling, top and bottom rails connecting the main posts with 25 each other, inclosing moldings inclosing the said main posts, extension posts, ceiling bars and rails, and panels carried by the said moldings.

A practical embodiment of the invention 30 is represented in the accompanying drawings forming a part of this specification, in which similar characters of reference indicate corresponding parts in all the views.

Figure 1 is a side elevation of the partition; Fig. 2 is an enlarged transverse section of the same on the line 2—2 of Fig. 1; Fig. 3 is an enlarged sectional plan view of the same on the line 3—3 of Fig. 1; Fig. 4 is an enlarged sectional side elevation of 40 the skeleton frame; Fig. 5 is an enlarged sectional plan view of the partition at a branch; Fig. 6 is an enlarged cross section of the partition at the transom, the section being on the line 6—6 of Fig. 1; and Fig. 7 is an inverted sectional plan view of one 45 of the hollow posts the section being on the line 7—7 of Fig. 2.

The partition is provided with a skeleton framework having main posts A and corner posts B, the posts being spaced suitable distances apart, and each main post A being formed of two channel irons A', A² having the edges of their side members abutting, as plainly indicated in Fig. 3. Each corner 50 post B is preferably made of an angle iron, as shown in Fig. 3, and the angle irons A',

A² and B are adapted to rest on the floor and extend a desired height according to the height of the room in which the partition is to be erected, the upper ends of the post being a distance from the ceiling. The bottom rails C, of channel iron, connect adjacent posts with each other, the ends of the bottom rails being connected with the posts by angle irons D riveted or otherwise fastened to the sides of the posts and the inner faces of the bottom members of the bottom rails C, as plainly indicated in Figs. 2 and 4. The upper ends of the posts A and corner posts B are connected with each other by top rails E fastened at their ends to channel iron brackets F attached by bolts G to the corresponding posts A and B and to the under sides of the brackets F are secured cornice rails H, preferably in the form of channel irons. A connecting rail I connects the adjacent posts with each other a distance above the bottom rail C and an intermediate connecting rail J connects the posts with each other at a point intermediate the cornice rail H and the connecting rail I. By the arrangement described a very substantial and comparatively light skeleton frame is provided.

In order to extend the partition to the ceiling, use is made of an extension skeleton frame arranged as follows: In each of the hollow posts A extends an extension post K in the form of a bar spaced from the channel irons A' and A² by spacing blocks K' through which the post K extend the bolts G so as to hold the extension post K in position in the hollow post A, at the same time projecting the post K the desired distance above the main post A. The upper end of each bar K is provided with a flange K², to which are riveted or otherwise secured horizontal ceiling bars L connected by expansion bolts N or similar means to the ceiling so as to give the desired rigidity to the extension skeleton frame. At each corner post B are extension posts K³ in the form of two bars, terminating at their upper ends in flanges K⁴ to which the corresponding ends of the ceiling bars L are attached, and the two extension posts K³ in each corner post B are rigidly connected with each other by angle iron K⁵ and one of the said posts is secured by the corresponding bolt G in position in the post B. It is understood that a spacing block K⁶ is interposed between the post K³ and the cor-

responding member of the angle iron forming the corner post B, as will be readily understood by reference to Fig. 4.

The posts A, B and K are provided with 5 inclosing moldings arranged as follows: The tubular inclosing molding for each post A consists of two sections O, O', of which the section O is provided at its sides with outwardly-bent flanges O² while the section O' is provided on its sides with inwardly-extending flanges O³ against which fit the flanges O². The flanges O³ form seats for the sides of the panels P, P', of which the panel P may be of sheet metal and the 15 panel P' of glass, and the panels P, P' are held in place against the flanges O³ by retaining moldings Q, of the usual form. Each corner post B is inclosed in a molding made in two pieces R and R', of which the 20 molding R is provided with four sides and is fastened to the outside of the two members of the angle iron forming the post B while the corner of the angle iron is covered by an angular molding R'. The moldings 25 R and R' carry the retaining moldings Q', Q² for engaging the sides of the panels P, P' at the corner posts. Each of the extension posts K is inclosed with a molding formed of two sections S and S' similar to 30 the molding sections O, O' to provide seats for the sides of the panel P in the upper or ceiling section of the partition, the panels being secured at the sides by retaining moldings S², as will be readily understood 35 by reference to Fig. 3. The corner extension posts K³ are inclosed by a molding formed of two sections S³ and S⁴ similar to the moldings R and R', and on the said moldings S³ and S⁴ are held retaining 40 moldings S⁵ and S⁶ for engagement with the corresponding sides of the ceiling panels P².

A molding T, of approximately U shape rests with its top on the connecting rail I, 45 and the lower ends fit against the outside of the side members of the bottom rail C, as plainly indicated in Fig. 2, and base bars T' fit against the outside of the lower portions of the side members of the molding T to 50 give the desired finish to the base of the partition. On the top of the molding T are secured spaced moldings T² and T³ forming between them a seat for the lower end of the panel P, the said moldings T², T³ being secured in position by screws T⁴ or other 55 means. A molding U incloses the rail J and this molding is made in two parts U' and U², similar in construction to the molding formed of the members O, O', that is, 60 the section U' is provided with outwardly-turned flanges U³ at the top and bottom, and the molding U² is provided with inwardly-turned flanges U⁴ engaged by flanges U³, and the bottom flanges U⁴ form seats 65 for the upper ends of the lower panels P

while the upper flanges U⁴ form seats for the lower ends of the panels P' supported at their sides on the seats formed by the flanges O³ and the moldings Q, as before explained. Retaining moldings U⁵ are attached to the 70 under side of the section U' of the molding U to fasten the panels P in place, and a similar molding U⁶ is secured to the top of the molding U for engagement with the lower ends of the panels P'.

To the under side of the cornice rail H are secured upwardly-extending cornice moldings H', H² which extend approximately to the level of the top rail, as will be readily understood by reference to Fig. 2, and to the under side of the cornice moldings H', H² are secured panel moldings H³, H⁴ for engagement with the upper ends of the panels P' to hold the latter in place. The cornice moldings H', H² are cut out at 85 the posts A, as plainly shown in Fig. 7, so as to permit of making the cornice moldings H' and H² of a length corresponding to that of the partition, if desired.

The top rails E are each inclosed by a 90 tubular molding E' provided with a seat E² for the lower end of the ceiling panel P² and a retaining molding E³ is attached to the molding E' for engagement with the lower end of the panel P². It is understood that 95 the sides of the panels P² are held in place by the moldings S', S² covering the auxiliary posts K as previously explained.

The ceiling rail L is inclosed by a tubular molding L' forming a seat L² for the 100 upper end of the ceiling panel P² held in place in the upper end by a retaining molding L³ attached to the molding L'. Ceiling moldings V connect with the moldings L' and abut against the under side of the ceiling, as will be readily understood by reference to Figs. 1 and 2. The lower panels P are preferably provided with additional moldings P³ fastened in place in the usual manner to give the desired ornamental appearance to the said panels P.

A door W, of sheet metal, is arranged between adjacent posts A and is connected by hinges W' to one of the doors, as indicated in Fig. 3. The corresponding molding sections O and O' at the door posts A are the same as on the other posts, and the corresponding retaining molding Q is omitted to provide a seat for the door, as indicated in said figure.

In case a transom P⁴ is used instead of one of the upper panels P² such transom P⁴ is connected at its sides by pivots P⁵ with the corresponding extension posts K and seats are provided at the moldings L' and E' 125 of the ceiling bar L and the top rail E to accommodate the upper and lower ends of the transom P⁴, as will be readily understood by reference to Fig. 6. The molding L' is for the purpose reinforced by a U-shaped 130

molding L^4 which forms a seat for a molding P^6 arranged on the top and bottom of the transom P^4 .

In case of a branch or a crossing partition, the post at such crossing is formed of an angle iron B' and a channel iron B^2 fastened at one side member to the terminal of the one member of the angle iron B' , as plainly shown in Fig. 5. The post is inclosed in moldings R^2 and R^3 and retaining moldings Q^3 and Q^4 are provided for the cross partition P^7 while the partitions P are held between the retaining molding Q^4 and Q^5 .

15 The extension post K^7 is formed of two abutting channel irons and the extension post is inclosed in moldings X and X' provided with pairs of retaining moldings X^2 , X^3 for the upper panels P^2 and the retaining moldings X^4 and X^5 for the extra upper cross partition (not shown).

Having thus described my invention, I claim as new and desire to secure by Letters Patent:

25 1. A metallic partition provided with posts, a base rail of channel iron extending from one post to another, attaching brackets connecting the base rail with the sides of the posts, a connecting rail having upturned ends attached to the posts a distance above the base rail, and a molding of approximately U-shape seated on top of the said connecting rail and engaging the said base rail on the outside thereof.

35 2. A metallic partition provided with hollow posts, a base rail of channel iron extending from one post to another, attaching brackets connecting the base rail with the sides of the posts, a connecting rail having upturned ends attached to the posts a distance above the base rail, a molding of approximately U-shape seated on top of the said connecting rail and engaging the said

base rail on the outside thereof, and base bars engaging the lower ends of the said 45 U-shaped molding opposite the sides of the base rail.

3. A metallic partition provided with a skeleton frame, comprising posts, a top rail connecting the upper ends of adjacent posts 50 with each other, a cornice bar of channel iron a distance below the said top rail and connected at its ends with adjacent posts, and cornice moldings attached to the under side of the said cornice bar and extending 55 upwardly approximately to the level of the said top rail.

4. In a metallic partition the combination of a plurality of hollow posts made in halves, a post extension secured inside of each post 60 and projecting above the same, each post extension being provided with an inclosing molding, horizontal ceiling bars connecting the upper end of one post extension with the upper end of another post extension, 65 and means for holding together the halves of the several hollow posts.

5. The combination of a plurality of posts, a plurality of post extensions each mounted 70 within a post and extending upwardly therefrom, each post extension being provided at its top with a portion bent horizontally, and a plurality of bracing members each extending from the horizontally extending portion of each post extension to the horizontally extending portion of some other post extension, and means for connecting the bracing members to the ceiling.

In testimony whereof I have signed my name to this specification in the presence of 80 two subscribing witnesses.

ALBERT H. LEVENE.
